COVER FOR FLATIRON STANDS

Ethel M. Prior, West Hartford, Conn.

Application August 18, 1944, Serial No. 550,009

1 Claim. (Cl. 248—117.3)

1

My invention relates to the class of devices within which a flatiron stand may be enclosed for the purpose of protecting articles of furniture upon which the stand may be set, and also for the purpose of preventing the flatiron stand from being unduly heated, and an object of my invention, among others, is to provide a device of this kind that shall effectively accomplish the purposes for which it is designed.

One form of my improved flatiron stand, in the construction and use of which the objects herein set out, as well as others, may be attained, is illustrated in the accompanying drawings, in which—

Figure 1 is a perspective view of my improved cover for flatiron stands as seen looking at the top.

Figure 2 is a similar view as seen looking at the bottom.

Figure 3 is a view in cross section on a plane denoted by the dotted line 3—3 of Fig. 1.

Figure 4 is a perspective view illustrating the manner of inserting the flatiron stand into the cover.

Flatiron stands in use at the present time are frequently composed of heat conducting material as metal, the type of stand in general use comprising two plates of suitable material spaced apart and one forming the base and the other comprising the top, the latter being supported by the former by means of legs. These stands are especially designed for use with electric flatirons and the inherent qualities of the stands make them more or less noisy, and the heat conditions have in numerous instances caused damage to articles of furniture on which the stand may rest when electric current has inadvertently been allowed to flow through the flatiron for considerable lengths of time with the flatiron resting upon the stand.

My invention overcomes these various objections as well as others by providing a cover that is an insulator both as to heat and noise, such cover being shown in the accompanying drawings in which the numeral 5 denotes the top of my improved flatiron stand cover that may be made generally in the shape of flatirons in common use at the present time, and as shown in Figs. 1 and 2 of the drawings. This top is formed from asbestos or other heat non-conducting material and of proper thickness to withstand the uses to which it may be put. A narrow border 6 of metal or other rigid material is secured to the edge of the cover by forming it into grooved shape and then closely squeezing the sides into close contact with

opposite sides of the cover. The rigidity of this material may be relied upon to securely hold it in place. A jacket or pocket is formed to enclose the stand, this jacket or pocket comprising in part 5 a binding and a bottom portion having their meeting edges 7 secured together and extending along the sides 8 of the jacket at about the center thereof that are turned up from the bottom 9 of the jacket.

10 The bottom 9 of the jacket extends across the bottom and partially up the sides as shown in Fig. 3 where the upper edges are secured in any suitable manner to the lower edges of the binding 10.

15 The binding 10 is extended around the back end where it is formed into a closing flap 11, the lower edge of which is secured to the bottom 9 in any suitable manner and the upper edge having one member 12 of each of a number of snap

20 fasteners suitably formed to engage the other members 13 of said fasteners formed in the back portion of the border 6, and as shown in Figs. 2 and 4.

It is not intended that the stand hereinafter

25 set forth shall be permanently enclosed within the jacket or pocket, it being, in fact, desirable in order to preserve the jacket or pocket from undue wear to remove the stand, in which case there is a flexibility between the top 5 and the bottom 9 30 which allows such parts to rest together without the presence of the stand, and this is a particular feature of my invention.

As thus constructed the jacket or pocket comprises a pointed end 14 and an open or back end

35 15 within which open end the flatiron stand may be inserted, such stand being illustrated in Fig. 4 and comprising top and bottom plates 16—17 joined by supports 18 of any suitable form and as shown in Fig. 4, said supports being secured 40 to the top and bottom plates in order to properly space said plates apart and support the top plate with a flatiron thereon.

The top 5 of the jacket or pocket is composed mostly of asbestos which is treated in any of the 45 well known ways to comprise a semi-stiff surface sufficiently rigid to, in itself, support a flatiron, although it would not serve such purpose in every day use and therefore the stand is provided to serve such purpose.

50 In order to render the pocket absolutely fire-proof the binding 10 is composed of a coarse grade of asbestos.

I claim:

A flatiron stand comprising a top composed of 55 a semi-rigid sheet of asbestos material, a bottom

of a flexible textile material having a surrounding upwardly projecting marginal portion, a binding of loosely woven asbestos material stitched to said portion along the edge thereof to provide a heat resisting and insulating portion between the said top and bottom, and a metallic border surrounding the said top and securing the said binding thereto.

ETHEL M. PRIOR.
